Clement L. Carter

UNITED STATES PATENT OFFICE.

CLEMENT L. CARTER, OF UNION CITY, INDIANA.

MACHINE FOR SHAPING POST-AUGER BLADES.

SPECIFICATION forming part of Letters Patent No. 326,399, dated September 15, 1885.

Application filed June 8, 1885. (Model.)

To all whom it may concern:

Be it known that I, CLEMENT L. CARTER, of Union City, of the county of Randolph and State of Indiana, have invented certain new and useful Improvements in Presses and Dies for Shaping Post-Augers, where it is desired to economize space, and utilize power where heavy pressure is needed, either by hand or power; and I do hereby declare that the following is a full, clear, and exact description of my invention, which will enable others skilled in the art to which it appertains to make and use the same, reference being had to the accompanying drawings, which form a part of this specification, and in which—

Figure 1 is a perspective view of my invention when used as a hand-power. Fig. 2 is an end view of the same with the convex die elevated and the concave die drawn out to receive the auger-blade; and Fig. 3 is a view of a post-auger blade as taken from the press in perfect shape.

Similar letters of reference indicate corresponding parts in each figure.

25 The object of my invention is to construct a cheap and efficient machine, with dies to match each other, for forming blades for my patent post-hole digger, patented June 5 and August 28, 1883, one of the dies being 30 concave and the other convex, to match with lever attachments so arranged that the dies can be brought together with great force, thereby giving the post-auger blade, placed between them, the proper shape, as hereinafter 35 more fully described and claimed.

In the accompanying drawings, R R indicate the frame on legs to support the working parts of my invention; D D, the frame or guides for the convex die B; C, the concave die; I, the shaft rigidly connected to the die B.

O is a strong shaft, passing through to the opposite side of the guides D D, forming a connection with the shaft I on the opposite side by means of a connecting-rod, (not shown in the drawings,) to correspond with the connecting-rod J. (Shown in Figs. 1 and 2.)

F is the lever for moving the concave die, as desired, for convenience in putting the post-auger blade in or removing it.

H is a lever, by means of which the convex die B is raised or pressed with force into the concave die C, to give shape to the post-auger blade; N, a guide for the concave die C.

I construct my match dies for forming post-auger blades in such a shape that the auger-blades formed by them are straight through the center from end to end, and have a varying arc from the upper to the lower end. In my post-hole digger referred to above the blades converge; hence the reason for the varying arc.

To explain more fully my invention as seen at Fig. 2, the convex die B is elevated, the concave die C being drawn out to receive the post-auger blade. The post-auger blade being placed on the concave die C in proper position, is, by means of the lever F and the connection M, brought immediately under the convex die B.

It will be seen that the connecting-rods J, at their connection with the shaft O at T, are on the upper side of the shaft O; and it will be further seen that by moving the lever H from right to left it will turn the point of connection at T to the opposite or lower side of the shaft O, thereby shortening the distance between the shafts O and I. The lever H being the long arm of the lever, the attachment at T the short arm, the shaft O the fulcrum, it will be seen that when the short arm T passes below the center of the shaft O its length diminishes as it approaches the line of the center of the shafts I and O, thereby giving increasing power.

Having thus described my invention, I claim as new and desire to secure by Letters Patent of the United States—

The combination of the dies B and C, the guides D D, the levers H and F, the connecting-rods J, the attachment T, and the shafts I and O, all as and for the purposes set forth.

CLEMENT L. CARTER.
